UNITED STATES PATENT OFFICE.

FRANK D. POWELL, OF CHICAGO, ILLINOIS, ASSIGNOR, BY MESNE ASSIGNMENTS, TO ACME CARD SYSTEM COMPANY, OF CHICAGO, ILLINOIS, A CORPORATION OF ILLINOIS.

VISIBLE CARD SYSTEM.

Application filed July 16, 1920. Serial No. 396,760.

This invention relates to improvements in visible card systems and refers more particularly to that type of system in which a plurality of overlapping cards are mounted in a frame in such a manner as to expose the lower edges of the cards which contain the identifying data.

I am aware that heretofore, overlapping cards have been mounted in a frame by means of detachable carriers or hangers as for example, in Anthony Patent No. 1,327,936, dated Jan. 13, 1920. I am also aware that a plurality of cards have been supported in a pocket member suspended from a carrier or hanger, which is itself mounted in a frame. In addition, heretofore a plurality of cards has been threaded on a hanger, which cards however cannot be removed from the hanger without first removing the hanger from the frame.

The present invention is distinguished from the above constructions and has advantages thereover, as will appear in the description hereinafter set forth.

In addition, there are conditions under which it may be desirable to provide each hanger with a plurality of cards, as for example, where it may be necessary or advantageous to have a maximum amount of data for any given subject and have such data immediately available. It may also be very convenient and desirable to have the data-containing slips removable or detachable from the hanger without removing the hanger from its frame member. Where easily soiled data-containing slips or papers are used, it will of course, be desirable to keep them clean.

The present invention affords all of the above advantages without necessitating an expensive or complicated structure and in fact without radically departing from the general type of structure to which the public using these devices is accustomed.

In the drawings:

Fig. 1 is a front view of my device with the central portion broken away.

Fig. 2 is a fragmentary end view of the same.

Fig. 3 is a perspective view (but showing the channel portion of the frame in dotted lines) of one of the units.

Fig. 4 is a view generally similar to Fig. 3, of a modified construction.

Referring in detail to the drawings, 1

designates the channel frame member, provided at either side of the body portion with channels 2, to receive the wire hangers 3. These wire hangers 3 are detachably sprung into the opposed channels of the frame members, as shown in the drawing and are provided with return bends 4. Detachably and movably supported from the return bends 4 of the hangers are the carriers 5. These carriers 5 may take the form of relatively stiff cardboards or they may be made of other material or may be transparent in whole or in part. The carriers are detachably mounted on the hangers by means of clips 6, which are preferably fixedly secured to the upper edge of the carrier and are provided with eyes 7, whereby they may be slipped on the inturned ends 4 of the hangers 3. The arrangement is such that these carriers can be mounted on the hangers either while the hangers are in the frame or are out of the frame. They can also be detached from the hangers in the same way.

Detachably mounted on the carriers are one or more data-containing the cards, slips or papers which are preferably made of lighter paper than the carriers and are so constructed that they can be readily slipped on and supported from the carriers. Describing these data-containing members more specifically, from each carrier 5 is supported a data-containing member 8, which is apertured or notched as shown at 9, 9, the arrangement being such that the notches readily slip over the eyes of the clips 6. Each of these members 8 comprises a front portion 10, and a rear portion 11, preferably in the form of a single sheet of paper. It is to be particularly noted that the front portion 10 may be somewhat shorter so that the card 5 (Figs. 2 and 3) extends below and exposes identifying data placed thereon. In addition, by mounting the member 8 in the manner just described, it will be entirely concealed from view and also protected from being soiled in the event that the carrier of the construction shown in Figs. 1 to 3 is used.

In Fig. 4, I have shown a modified construction which is exactly similar to the one previously described, except that the card carrier 5' does not extend down so as to cover up the data-containing member but extends

only sufficiently to form an effective support from which the data-containing papers can be suspended. In this modified construction, it is not necessary to have the indexing or identifying data applied to the exposed lower margins of the card carriers as is the case in the construction shown in Figs. 1 to 3 inclusive. In this modified form, the exposed edges of the overlapping data-containing papers will contain the necessary identifying information.

I have heretofore stated that the carriers 5 in Figs. 1 to 3, may be made transparent in whole or in part. This can be accomplished by making the members 5 of transparent celluloid and different colored carriers may be used, if desired or the carrier may have a transparent window which can be accomplished by cutting an aperture in 20 an opaque card and closing said aperture with transparent celluloid.

I claim as my invention:

1. In a device of the character described, the combination with a frame member, of a plurality of hangers detachably mounted therein, a card-simulating carrier detachably suspended from each hanger, and one or more data-containing members folded across and supported by each carrier.
2. In a device of the character described, the combination with a frame member, of a plurality of resilient metal hangers detachably mounted therein, a card-simulating carrier detachably suspended from each hanger, and one or more data-containing members folded across and supported by each carrier.
3. In a device of the character described, the combination with a frame member, of a plurality of hangers detachably mounted therein, carriers detachably suspended from the hangers, taking the form of flat card members, and one or more data-containing members folded across and supported by each carrier.
4. In a device of the character described, the combination with a frame member, of a plurality of hangers detachably mounted therein, a card-simulating carrier detachably suspended from each hanger, and one or more separate data-containing members of relatively thin paper folded across and supported by each card-simulating carrier.
5. In a device of the character described, the combination with a frame member, of a plurality of hangers detachably mounted therein, a card-simulating carrier detachably suspended from each hanger, and one or more data-containing members folded across

and supported by each card-simulating carrier, said card-simulating carriers with the data-containing members being detachable from the hangers, either while the latter are in the frame or removed from the frame.

6. In a device of the character described, the combination with a frame member, of resilient metal hangers detachably mounted therein, individual carriers detachably suspended from individual hangers taking the form of flat card members and one or more data-containing members taking the form of relatively thin paper folded across and supported by each carrier, said carriers with the data-containing members, being detachable from the hangers, either while the latter are in the frame or removed from the frame.

7. In a device of the character described, the combination with a frame, of resilient hangers supported adjacent each other on said frame, carriers taking the form of cards detachably supported by the hangers, and a plurality of folded sheets supported at their folded margins by the card carriers.

8. In a visible card system, the combination with a flanged frame, of resilient hangers supported near their extremities by the flanges of the frame and supported adjacent each other, stiff card-simulating carriers detachably supported by the hangers and a plurality of folded substantially flexible sheets supported at their folded margins by 90 the card-simulating carriers.

9. In a visible card index, the combination with a flanged frame, of resilient hangers supported by the flanges of said frame and held adjacent to each other, carriers taking the form of relatively stiff cards detachably supported by the hangers and folded substantially flexible index sheets supported at their folded margins by the carriers.

10. In a device of the character described the combination with a frame, of resilient spacing hangers removably supported in the frame, card-simulating carriers attached to the hangers, folded sheets supported at their folded margin by the card-simulating carriers and removable therefrom without removing the hangers from the frame.

11. In a device of the character described the combination with a frame, of resilient hangers removably supported by the frame, 110 cards hinged to the hangers, folded data sheets supported along their folded edges by the cards and removable therefrom without removing the hangers from the frame.

FRANK D. POWELL.
